UNITED STATES PATENT OFFICE.

HERON S. E. DIXON, OF HYDE PARK, ILLINOIS.

AIR-BRAKE.

SPECIFICATION forming part of Letters Patent No. 412,168, dated October 1, 1889.

Application filed July 22, 1889. Serial No. 318,296. (No model.)

To all whom it may concern:

Be it known that I, THERON S. E. DIXON, a citizen of the United States of America, residing at Hyde Park, in the county of Cook and State of Illinois, have invented certain new and useful Improvements in Air-Brakes, of which the following is a specification.

Referring to the accompanying drawings, wherein similar reference-letters indicate the same or corresponding parts, Figure 1 is a plan view showing the general arrangement; Fig. 2, a section illustrating the preferred form of governing-valve to be used with my present improvement; Fig. 3, a longitudinal vertical section of limiting-valve E, taken in line 3 3 of Fig. 4; Fig. 4, a transverse vertical section of the same, taken in line 4 4 of Fig. 3; Fig. 5, a vertical section of the limiting-valve E^x; Fig. 6, an elevation of a jacketed air-pump, having a portion of the outer wall broken away; Fig. 7, a section showing the typical construction of the differential regulating-valves; Fig. 8, a horizontal section showing the practical application of the differential regulating-valves; Fig. 9, a partial vertical section of the way-cock and one of the differential regulating-valves; Fig. 10, a partial elevation of the way-cock, showing portions in vertical sections; Fig. 11, a horizontal section in line 11 11 of Fig. 10, and Fig. 12 a horizontal section of the cut-off cock A² and its connections.

In the following specification and claims for purposes of brevity I use the term "way-cock" to denote the engineer's valve or other device operated by the attendant to initiate or produce variations of train-pipe pressure, the term "governing-valve" to indicate the valve device, whereby such variations control the brake-cylinder ports, and the term "brake mechanism" as meaning the group of instrumentalities, under each car, consisting of the brake-cylinder, auxiliary reservoir, and governing-valve coacting together. I regard as general equivalents a cock and a valve, a diaphragm, and a piston, and where I describe a spring for producing differential action upon a valve I intend to include its known equivalents for that purpose—such as a weight, a differential piston or diaphragm, an independent column of fluid under pressure—and

I use the term "differential valve" to indicate a valve capable of being moved in one direction by a fluid-pressure insufficient to move it in the opposite direction. In mentioning 55 pounds of air-pressure I mean pounds per square inch.

This invention relates more particularly to that class of air-brakes commonly known as "automatic air-brakes," in which an air-pump 60 actuated by the steam-pressure of the locomotive-boiler compresses air into a main reservoir, or main reservoirs, on the engine or tender, from which it is delivered to the train-pipe, and thence to the auxiliary reservoirs 65 along the train, and from them to the several brake-cylinders, the auxiliary reservoirs being charged by venting air from the main reservoir or main reservoirs into the train-pipe, and the brakes being applied at the will of 70 the engineer by sufficiently reducing the pressure in the train-pipe and released by sufficiently increasing such pressure.

While applicable in many different forms of air-brake and vacuum-brake apparatus, 75 my present invention will best attain all its advantages when employed in connection with the brake apparatus for which Letters Patent of the United States of America were granted to me, dated April 30, 1889, No. 402,418, 80 a portion of which, merely for purposes of illustration, is outlined in Fig. 2.

A, Fig. 1, represents one of the auxiliary reservoirs; B, one of the brake-cylinders; D, the train-pipe; and in Fig. 2, C indicates the 85 governing-valve having a main valve c and a supplementary valve c', and provided with a spring c² to arrest the outward movement of the main valve when it arrives at the service-port, as will more fully appear by reference to my said patent.

The objects of my present invention are, first, to increase the general efficiency and reliability of the automatic air-brake system; and, secondly, to enable the engineer to operate it easily and without danger of error.

To these ends my invention comprises, first, improved means for enabling the main reservoir or reservoirs to carry unlimited pressures, but vent only the properly limited pressure into the train-pipe; secondly, means for increasing the efficiency of the air-pump for the

production of such high pressures; thirdly, means for automatically regulating the flow of air to and from the train-pipe when the way-cock is open; and, fourthly, an improved 5 method of controlling said automatic regulation.

Other improvements will be sufficiently indicated by the description and the claims appended thereto.

10 These improvements may be used conjointly or separately, and in various forms of apparatus, the form here illustrated being preferred because it enables me to combine them in a structure which occupies but little room in the locomotive-cab, and to operate them by a simple form of way-cock having substantially the same movements as those of the old and well-known way-cock already familiar to locomotive-engineers. I will now proceed 15 to describe them in the order above indicated.

15 The old reducing-valve arranged in the way-cock or in the passage leading from the main reservoir to the train-pipe, for the purpose of reducing the normal pressure of the latter about twenty pounds below the pressure in the former, is objectionable for at least two reasons—viz: first, it involves the practical necessity of employing devices to regulate or limit the action of the air-pump in 20 order not to charge the main reservoirs too high, and thus unduly limit their storage capacity; and, secondly, it unduly limits the maximum pressure of the train-pipe when the main reservoir has become partially depleted. The true principle is to charge the 25 main reservoirs to their full capacity, and to employ in said passage a limiting-valve, which will automatically close it when the train-pipe pressure reaches its allowed maximum, 30 but leave the passage free at all other times. Attempts have already been made to apply this principle, but by devices more or less defective in their operation.

One of my improvements consists in combining with the train-pipe and main reservoir 40 a valve which is opened by a force independent of the main-reservoir pressure and closed by a rise of train-pipe pressure sufficient to overcome said force, and which, when closed, 45 is tightly held to its seat by the superior pressure of the main reservoir. The best form in which I have contemplated the application of this improvement is as follows:

Assuming by way of illustration that the 50 ordinary maximum limit of pressure allowable in the train-pipe and auxiliary reservoirs for working purposes should be, say, sixty pounds to the square inch, and that for quick and certain release of the brakes when the 55 auxiliary reservoirs are full or nearly full the engineer should be able to raise the train-pipe pressure for a few moments—say, twenty-five pounds higher than this limit—till the release is effected. I provide as usual two passages, 60 or a passage having two branches o from the main reservoir to the train-pipe, both con-

trolled by the way-cock, one of which passages or branches o' (herein termed the "sixty-pound passage") is intended to raise the train-pipe pressure to the sixty-pound limit, and the other o (herein termed the "eighty-five-pound passage" or "high-pressure passage,") is intended to raise the train-pipe pressure to a possible maximum of about eighty-five pounds, using one main reservoir, 70 or two O 's, as may be preferred by the constructor. In the sixty-pound passage I place the limiting-valve device E, Figs. 3 and 4, the construction of which is as follows:

E' is the valve-casing pump containing 80 two chambers E^2 E^3 , separated by a valve-seat E^4 , provided, preferably, with two ports e and a central recess e' . E^5 is a slide-valve seated on the partition E^4 , having ports to register with the ports e , and preferably held 85 to its seat by a spring E^6 .

E^7 is a diaphragm, subject at its inner side to the air-pressure in chamber E^3 and at its outer side to atmospheric pressure and the action of a strong spring E^8 , which tends to hold it normally at the inner limit of its traverse.

E^9 is a screw-cap, serving to inclose and adjust the spring; and E^{10} is a rod, suitably guided at e^2 , which, by means of an arm E^8 , 95 connects the diaphragm E^7 to the slide-valve E^5 , so that movements of the former will 100 actuate the latter to open and close the ports e . Preferably the rod or stem E^{10} is passed through a hole in the arm E^8 , which it accurately fits and is secured by a screw e^4 , the end of the arm extending into a recess in the valve E^5 , and slightly rounded at the lateral points of contact, so that the valve while responding to the slightest movement of the 105 stem will be able at all times to adjust itself accurately to its seat, as it would not be able perfectly to do were the arm integral with the valve, instead of being, as here shown, practically integral with the stem. The spring E^8 110

is to act with a force equal to, say, sixty pounds air-pressure per square inch on the diaphragm, and should be adjusted accordingly. I prefer to make the diaphragm of rubber faced with filled leather or other suitable material to protect the rubber from the oil contained in the air after its passage through the air-pump. The diaphragm is subject to effective air-pressure only on one side, and to support it against this pressure 115 I arrange behind it a block E^{11} , closely fitting the walls of the chamber which incloses the spring and slightly round the approximate corners of the block and the casing, as shown at e^5 e^6 , so as to present convex surfaces to 120 the diaphragm instead of the concave surfaces hitherto generally employed in connection with a flexible diaphragm, and thus more effectually support the diaphragm.

In the passage leading from the limiting-valve to the train-pipe the constructor may, if he prefers, place a check-valve seating back-

ward toward the limiting-valve; but I do not deem it necessary to illustrate the check-valve, as its form is well known to mechanics.

The operation is as follows:

5 First. When the way-cock is turned to the proper position, the eduction end of the passage o' is put into communication with the train-pipe, and the diaphragm E' is therefore subject to train-pipe pressure. So long as 10 this is below sixty pounds spring E^8 will hold ports e^e open and allow air to pass freely from the main reservoir to the train-pipe; but the moment it rises above sixty pounds it will 15 overcome the spring force, close said ports, and cut off the flow, no matter how much the main-reservoir pressure may exceed the sixty-pound limit. The superior force of the main-reservoir pressure tends to hold the limiting-valve to its seat when closed, rendering its 20 operation reliable and effective for the purposes of its use under all conditions of service.

Second. In the passage o a limiting-valve similar to that above described may be used, if preferred, but adjusted to a limit of, say, 25 eighty-five pounds instead of sixty pounds. In this passage, however, I prefer to employ at E^x , as a limiting-valve, the construction shown in Fig. 5, in order to insure a very copious flow during the brief period while this 30 passage is open to the train-pipe. In this figure $e^{20} e^{21}$ are two coned annular valve-seats, the smaller end of the larger seat being equal in diameter to the larger end of the smaller seat and in line therewith, so that the valve 35 e^{22} , having faces $e^{23} e^{24}$ corresponding to said seats, can readily be introduced and ground to a perfect bearing. An annular recess e^{25} is made in the wall of the casing between the valve-seats, and a corresponding recess e^{26} in 40 the valve between its bearings, so that air at the induction side of the valve will extend entirely around it, balancing it both laterally and longitudinally. A passage e^{27} extends centrally through the valve, and is spanned 45 by an arm e^{28} , to which the valve-stem E^{10} is fastened by a screw-nut or other device e^{29} . The stem is connected to a diaphragm E^7 , actuated by air-pressure at its inner face and by the eighty-five-pound spring E^8 at its outer 50 side, as already described. I prefer to make the diaphragm of steel, tempered, nickel-plated in the rough, and lined with brass or German silver to protect it from corrosion. I also prefer to arch the casing above the valve, 55 as shown at e^{30} , in order to deflect the air-currents downward through the central opening e^{27} , providing passages e^{31} to admit air-pressure to the face of the diaphragm. With this construction when the valve unseats, air will 60 vent around it both upward and downward in the directions shown by the arrows through spaces of such great length that a slight opening movement will produce an ample discharge. When the air thus vented reaches a 65 pressure of eighty-five pounds to the inch at the eduction side of the valve-ports, the valve

will automatically close and stop further increase.

To insure a quick and certain release of the brakes at any time, it is only necessary that 70 the train-pipe pressure should be raised for a moment about twenty-five pounds higher than the auxiliary-reservoir pressure existing at the time, and any greater increase of train-pipe pressure than this is for many reasons 75 undesirable. As a further improvement, therefore, the constructor may, if he prefer, set the spring E^8 , Fig. 5, at about twenty-five-pounds pressure, and by a pipe A' (shown in Fig. 5 in dotted lines) admit to the back 80 of the diaphragm E^7 air from one of the auxiliary reservoirs, preferably the one in use on the tender. In such case whenever the way-cock is open to admit air from the main reservoir through the passage o to the train-pipe, 85 the pressure in the train-pipe will rise twenty-five pounds higher than the pressure existing in the auxiliary reservoirs along the train, and thereupon the limiting-valve will automatically cut off the rapid flow, and the 90 brakes being now released the engineer will close the way-cock to prevent the auxiliary reservoirs from attaining too high a pressure.

If from defective construction or long use the diaphragm E' of Figs. 3 and 5 should accidentally break, the engineer can readily close the spring-containing chamber by turning the screw-cap E^9 , and thereby prevent loss of main-reservoir air, the chamber having a vent-hole e^{50} , which in Fig. 3 is closed by screwing 95 the cap down, and in Fig. 5 by merely turning the cap.

Fig. 1 shows the service-main reservoir O and reserve-main reservoir O' of my said patent, the connections to the air-pump being 105 effected by a pipe o^4 , provided with a check-valve o^5 , seating toward the service-main reservoir.

Third. In charging the main reservoirs even to the limited pressure heretofore allowed, 110 the air-pump has been liable to occasionally become heated, and when heated its working capacity is known to be considerably impaired. In charging to the high pressures now rendered available by substituting limiting-valves for the old reducing-valve, the air-pump will be rendered still more liable to overheating, and therefore I provide means for obviating this difficulty. To this end I jacket the air-pump P , or so much thereof as 115 may be necessary, with the jacket shown at P' , Fig. 6, and connect the feed-water pipe P^2 from the tank to the chamber within the jacket, and thence to the feed-water pump or injector P^3 , Fig. 1, so that the latter will draw 120 or force the feed-water through the jacket and in contact with the walls of the pump, and the current thus established will carry off and utilize any excess of heat that may be 125 liberated by the action of the pump. The same provision protects the pump from freezing in extremely cold weather. This improve-

ment will be an advantage in all cases where an air-pump is used on the locomotive.

Fourth. In three of my improvements—viz., the means for applying the brakes or grading up their pressure at will without accidentally applying the emergency-stop, the means for grading down their pressure at will without accidentally releasing them, and the means for refilling the auxiliary reservoirs without releasing the brakes—I combine the way-cock with an automatic differential valve in such a manner that the turning of the way-cock to a predetermined position in each case will cause the train-pipe pressure to be preliminarily increased or reduced to the desired extent above or below the auxiliary-reservoir pressure, and thereupon the valve will take control of the train-pipe pressure and automatically maintain substantially the relation thus established so long as the way-cock remains open, even though the auxiliary-reservoir pressure be meanwhile reducing by venting into the brake-cylinders, or increasing by refilling from the train-pipe. This important result I accomplish by means of a supplementary device, termed by me the "differential regulating-valve," consisting, essentially, in a differential valve controlled by two opposed fluid-pressures, one of which is in turn controlled by the valve and also by the way-cock, the differential force being so applied as to aid the fluid-pressure, which tends to hold the valve-port open, or, as the equivalent thereof, to resist or reduce the effective action of the fluid-pressure which tends to hold said port closed. One of these two fluid-pressures serves as a controlling or regulating force; the other as the pressure which is to be directly controlled or regulated thereby. For the former the constructor may employ any fluid-pressure whose initial force and rate of variation therefrom adapt it to the purpose. For the latter he will employ the train-pipe pressure itself, or some fluid-pressure which, by suitable mechanism, governs the train-pipe pressure, the ultimate object being to so control the train-pipe pressure directly or indirectly as to cause it to assume and to maintain at the will of the engineer such a relation to the auxiliary-reservoir pressure as is competent to effect the desired result at the governing-valves along the train without producing any undesired result. The principle of operation involved consists in causing the opening of a passage by the way-cock to freely increase or reduce the regulated pressure to a given extent and then causing the differential valve to take control of said passage and automatically regulate its flow to a substantial correspondence with that which may be taking place at the time into or out of the receptacle containing the regulating-pressure, thereby continuously holding the regulated pressure in the desired relation to the regulating-pressure, whether the latter be the regulating-pressure, whether the latter be meanwhile subject to variation or not, and

whatever may be the means employed to produce such variation.

While, as above stated, the differential regulating-valve is adapted to operate with any suitable regulating fluid-pressure, great practical advantages result from the direct use of the auxiliary-reservoir pressure itself as the controlling or regulating force, and one of my inventions resides in the new method, or improvement in the art, involved in the employment of the auxiliary-reservoir pressure as a regulating-force to regulate the flow of air into or out of the train-pipe at the engine when the way-cock is turned to the proper position therefor. Coming now to the mechanical embodiment of these principles, the differential regulating-valve is typified in the device shown in Fig. 7, wherein F F' are two fluid-pressure chambers or receptacles of any preferred form, separated from each other by a flexible diaphragm G. G' is a valve connected to and operated by the diaphragm G, and provided with a port g, which acts in conjunction with a port or passage h in the wall of the casing, and G² is a spring acting against the diaphragm or valve. The movement of the diaphragm may be limited by stems g' g² striking against stops g³ g⁴, and wooden blocks or other sound-deadening material g⁵ may be interposed to receive the impact of the stems against the stops. The spring is employed to aid the air-pressure in one direction and thus render the valve differential in its action, and the effective force of the spring determines the amount of the differential. If strong springs are preferred, they may readily be employed by arranging two of them so as to oppose each other's action, and making one sufficiently stronger than the other to create the differential required—for example, by placing a spring at each side of the diaphragm. If it be desired to limit the possible decrease of fluid-pressure in chamber F to a certain number of pounds below that in chamber F', then the port g will be so arranged and the spring-force so applied that the fluid-pressure in chamber F plus the spring-force will tend to hold the port g h open against the resistance of the fluid-pressure in chamber F', and the passage h will be arranged to communicate with the atmosphere and will be used as an exhaust. On the other hand, if it be desired to limit the possible increase of fluid-pressure in chamber F to a certain number of pounds above that in chamber F', then the port g will be so arranged and the spring force so applied that the fluid-pressure in chamber F plus the spring force will tend to hold the port g h open against the resistance of the fluid-pressure in chamber F, and the passage h will be arranged to communicate with the sixty-pound passage from the main reservoir and used as a supply-port. The former, termed by me "differential regulating-valve No. 1," is the arrangement shown at L, Fig. 8,

for reducing the train-pipe pressure a given number of pounds below the auxiliary-reservoir pressure, to apply the brakes or grade up their pressure at will without danger of accidentally applying the emergency-stop; and the latter, termed by me "differential regulating-valve No. 2," is the arrangement shown at M, Fig. 8, for increasing the train-pipe pressure a given number of pounds above the auxiliary-reservoir pressure to grade down the brake-pressure at will without danger of accidentally releasing the brakes, and also shown at N, Fig. 8, for increasing the train-pipe pressure to a smaller extent above the auxiliary-reservoir pressure, to automatically refill the auxiliary reservoirs without accidentally releasing the brakes.

Fifth. For applying the differential regulating-valves No. 1 and No. 2 to their respective uses the simplest and best form of means which I have contemplated is as follows: J, Figs. 8, 9, and 10, is a casting adapted to support the several members. I is a hollow conical way-cock so arranged in casting J as to communicate at its lower end with the train-pipe and provided with two ports *i* *i'* through its wall. Through the wall of the casing J are arranged, preferably, six ports, viz: A port *k*, leading to the atmosphere; a port *l*, leading to chamber F of differential regulating-valve L; a port *m*, leading to chamber F of differential regulating-valve M; a port *n*, leading to chamber F of differential regulating-valve N; a port *o'*, communicating with the sixty-pound main-reservoir pipe *o'*, and a port *o*², communicating with the high-pressure pipe *o* from the main reservoir. In each of the differential regulating-valves the chamber F' communicates, through the pipe A', with one of the auxiliary reservoirs, preferably the one in use in the brake mechanism of the tender. The port *h* in regulating-valve L communicates with the atmosphere, in regulating-valve M with the sixty-pound pipe *o'*, and in regulating-valve N, preferably by a pipe or passage R, with chamber F of regulating-valve M, although it may communicate directly with the sixty-pound pipe *o'*, if preferred. It is best to connect pipe A' to the lower side of chambers F' and ports *l* *m* *n*, at the lower edge of chambers F, to drain off any water that may deposit in said chambers. In the differential regulating-valves L M the spring should be adjusted to act with an effective force equal, say, to three pounds fluid-pressure on diaphragms G, and in differential regulating-valve N to act with a force of, say, one pound fluid-pressure on the diaphragm.

60 The operation is as follows:

First. Upon turning the way-cock, so as to bring port *i* to port *k*, the train-pipe pressure will suddenly exhaust to the atmosphere and apply the emergency-stop.

Second. Upon turning port *i* to port *l* the train-pipe pressure will reduce three pounds below the auxiliary-reservoir pressure and

apply the service-stop, or grade up the brake-pressure, if it has already been applied. In either case the auxiliary-reservoir pressure 70 will reduce by venting into the brake-cylinders along the train; but through the action of the differential regulating-valve the train-pipe pressure will reduce with it and keep just three pounds below it so long as the 75 way-cock is open. This continues to hold the service-ports open and grade up the brake-pressure. When the engineer is satisfied with the amount of brake-pressure obtained, he closes the way-cock and stops further increase; or he may, if he desires, allow the brake-pressure to run up till the brake-cylinders and auxiliary reservoirs equalize, whereupon the valve G will automatically close port *h* and stop further outflow from the 85 train-pipe.

Third. Upon turning port *i* to port *m* fluid-pressure from the sixty-pound pipe *o'* will pass through chamber F of regulating-valve M to the train-pipe and raise the pressure of 90 the latter three pounds above the auxiliary-reservoir pressure. This, with my brake mechanism patented April 30, 1889, will move the supplementary valves *c'* inward without disturbing the main valves *c*, and will thereby 95 open a leak from the brake-cylinders to the atmosphere and grade the brake-pressure down. During the operation, if the governing-valves are provided with equalizing-ports, as contemplated in my said patent, the air 100 will slowly equalize from the train-pipe to the auxiliary reservoirs, thus tending to reduce the pressure in the former and raise that in the latter; but the differential regulating-valve M will automatically keep the 105 train-pipe pressure three pounds higher than the auxiliary-reservoir pressure so long as the way-cock is open, notwithstanding such action of the governing-valves. Whenever the way-cock is closed, the equalization referred 110 to will immediately cause the governing-valves to close the leak from the brake-cylinders. Hence this device enables the engineer to grade the brake-pressure down at will without danger of accidentally releasing the 115 brakes. If the governing-valves are not provided with equalizing-ports, then the differential regulating-valve will allow the train-pipe pressure to rise three pounds above the auxiliary-reservoir pressure and will hold it 120 there, the regulating-valve itself remaining open only so far as is necessary to supply the loss occasioned by any accidental leakage from the train-pipe, and in this case the engineer stops the grading down whenever he 125 desires by discharging a pound or two of air-pressure from the train-pipe.

Fourth. Upon turning port *i* to port *o*² air at sixty-pounds pressure will vent freely into the train-pipe and release the brakes if the 130 auxiliary reservoirs are not already substantially refilled. If they are, the way-cock should be turned to the next port to release the brakes.

Fifth. Upon turning port i to the next port o^3 air at a pressure twenty-five pounds higher than that existing at the time in the auxiliary reservoirs will vent into the train-pipe 5 and insure the quick release of the brakes.

Sixth. After the engineer by turning the way-cock to any of said positions has effected the result desired, he turns it back to the normal position, wherein port i' communicates with port n . Air reduced in chamber F of regulating-valve M to a pressure three pounds above the auxiliary-reservoir pressure now passes through pipe R to regulating-valve N , where its head of pressure is reduced to, say, one pound above the auxiliary-reservoir pressure, and it is thence vented through the feed-ports n i' to the train-pipe. This small increase of train-pipe pressure is insufficient to move the supplementary valves c' of the governing-valve apparatus along the train, but will vent through suitable refilling-passages provided therefor into the auxiliary reservoirs and slowly refill them to their allowed maximum of sixty pounds, the regulating-valves M N holding the train-pipe pressure just one pound higher than the auxiliary-reservoir pressure so long as the refilling is taking place. The engineer leaves the way-cock in this position to supply any accidental leakage through the couplings. The refilling-passages may be provided in the governing-valve devices along the train by suitably enlarging the small equalizing-leak described in my patent of April 30, 1889, or in any other appropriate manner. In those positions of the way-cock which open the ports i l , i m , or i' n the train-pipe pressure can never rise above or fall below the auxiliary-reservoir pressure to an amount exceeding the differential force of the spring; hence no effect upon the governing-valves which requires a greater variation of pressure can possibly be produced. To accomplish precisely the result which he desires in each instance, the engineer is therefore required to exercise no judgment or skill, but merely to turn the way-cock to the proper port, and when the result is seen to have been accomplished turn it back to the normal. At the normal the feed-port i' n is open and the apparatus at once commences automatically to refill the auxiliary reservoirs to their allowed maximum of sixty pounds, whether the brakes be held set or released. In a brake system thus guarded against accident the springs c^2 of the governing-valves may be set at eight or ten pounds resistance instead of fifteen or twenty, as heretofore, and the emergency-stop be thereby rendered considerably quicker of application. It will be observed that when in action the valves G' , controlled by the varying auxiliary-reservoir pressure, never quite close the ports g h but simply regulate their capacity to the requirements of the occasion, furnishing an automatically-regulated flow which holds the two opposing pressures in the exact relation de-

sired. This automatic action in applying the brakes for a service-stop prevents any accumulation of fluid-pressure in the front end of the train-pipe tending to accidentally release the brakes on the forward cars when the way-cock is suddenly closed, because at the moment when the way-cock is thus closed the vent that is taking place from the train-pipe is very slow, being equal only to that which is taking place from one auxiliary reservoir into its brake-cylinder, and hence no material "ram" of air-pressure is effected by such closing.

Seventh. Another provision also enables me to counteract the effect of any such ram and generally to render the movements of air in the train-pipe equable and uniform. This provision consists in an expansion-chamber D' at the forward end of the train-pipe made, preferably, by simply enlarging the diameter of said pipe immediately behind the way-cock. An outflowing air-current suddenly stopped by closing the way-cock, or an inflowing current suddenly produced by opening the way-cock will initially crowd the expansion-chamber and then flow back through the smaller train-pipe much more regularly and equably than when such chamber is not employed. Should air accumulate by leakage in any of the small chambers F while the way-cock is closed and vent suddenly through the way-cock when opened, this provision will distribute its momentary pressure through the expanding-chamber, and so reduce its head as to prevent it from producing any disturbing effect upon the sensitive governing-valves. As one result of the expansion-chamber a relatively small train-pipe may be used with corresponding economy of air in practically operating the system.

Eighth. In order to save room in the cab and to produce a way-cock of neat and handsome appearance, I design attaching the casting J to the floor of the cab, and preferably to the under side thereof, where it will be out of sight as well as out of the way, and bolt-holes j are provided for its attachment to the floor. In such case I screw a vertical tubular standard J' to the upper end of the casting J , leaving a space j' , if desired, to be filled with oil through a hole j^3 and used as a lubricating-chamber. A tube or rod I' , constituting an operating-shaft or spindle, extends up through the standard J' and supports the handle I^2 at its upper end, connection being made from tube I' to cock I by a block I^3 , attached to the tube and stepped into a recess in the end of the cock, and from tube I' to handle I^2 by a block I^4 , attached to the tube and fitting into a recess in the under side of the handle. Immediately above the block I^4 the upper surface of the handle is recessed, as shown at i^2 . A curved plate J^2 extends from tube J' up over recess i^2 , and a screw-bolt J^3 , screwing down through said arm, fits into the recess i^2 and serves to regulate the friction of cock I against its conical seat, or

in other words, to resist the tendency of the train-pipe pressure to loosen cock I in its seat. By this provision the cock is made to work with very little friction, and yet is kept perfectly air-tight, and it may at any time be readily and conveniently adjusted in these respects. I prefer a tubular to a solid rod I', merely because it is less liable to bend or buckle under the force of the adjusting-screw.

5 ⁷⁰ An indicating-plate T is attached to the over-hanging end of the curved plate J², so as to lie in a horizontal position just above the shank of the handle I², and a retaining-spring T', attached to the under side of the handle, comes 15 up through a slot therein and bears against the inner edge of the indicating-plate, which is provided with suitable notches or shoulders to mark the several operative positions of the handle and properly retain it therein. The 20 peculiar arrangement described exposes the indicating notches or shoulders at the upper side of the plate and outside of the spring, and thus enables the engineer to see them much more readily and easily than when arranged as heretofore.

Whether the brakes be held set or released the handle will normally be carried at the feed position, (marked w, Fig. 11,) where it automatically refills the auxiliary reservoirs 25 to their allowed maximum without disturbing the brakes. One point to the right, at w', it will apply the service-stop or grade up the brake-pressure at will without applying the emergency-stop. At the extreme right w² it 30 will apply the emergency-stop. At u, one point to the left of the normal position, it will grade down the brake-pressure at will and incidentally increase the auxiliary-reservoir pressure without releasing the brakes. At u', 35 two points to the left, it will release and refill, and at w², the extreme left, it will quickly release and refill. If the train should contain cars not adapted to the refilling of the auxiliary reservoirs, with the brakes held set, 40 the handles can be carried while the brakes are set at the small notch marked v immediately at the right of the normal position w, in which case the feed-port i' n will be held closed and out of action. It will be observed that all positions which decrease the train-pipe pressure 45 and apply the brakes, are at the right of the notch v, (as the engineer stands,) in the order of the violence of their action, and all positions which increase the train-pipe pressure 50 and refill or release, or both, are at the left of said notch, in similar order, so that, without gross negligence, no mistake can occur, either as to the direction or extent of the movement of the handle in the practical operation of the 55 system for the different purposes herein referred to. The extreme simplicity and certainty of operation will be appreciated when it is observed that at its normal position the handle holds the brakes in whatever position 60 they may have assumed, while if moved one point to the right it gradually raises their pressure, and if moved one point to the left

it gradually lowers their pressure, the amount of increase or decrease depending entirely upon the length of time during which it is so held.

70 I prefer to use the auxiliary reservoir of the tender to supply air to chambers F', because it is always with the engine, and therefore available. In such case the brake mechanism of the tender should preferably be of the 75 same dimensions as those of the other cars, in order to insure uniformity of action, and if, when so constructed, its brake force be too great for the tender, a resisting-spring may be arranged to take up a portion of such force, 80 as shown at Q, Fig. 1.

In the refilling feed-passage i' n a further principle comes into operation. The amount of air which ought to be fed to the train per second necessarily depends upon the number 85 of auxiliary reservoirs to be simultaneously refilled along the train, and the amount of air that will be fed per second through a passage of any given size depends upon the head of pressure forcing the air through said passage; hence, in order to feed a full supply 90 without danger of accidentally releasing the brakes, both the capacity of the feed-port and the head of pressure feeding through it should be capable of regulation. With the differential regulating-valve N applied as described, 95 both of these objects are attained, the valve automatically adjusting the capacity of the feed-passage at the engine to the capacity of the aggregate number of refilling-ports in operation along the train, and the head of pressure being rendered uniform whether the difference between the train-pipe pressure and main-reservoir pressure be great or little.

100 In case any or all of the three regulating-valves should accidentally get out of order, the brake system can be temporarily operated for applying and releasing the brakes and refilling the auxiliary reservoirs by the other way-cock ports. In such case it may be desirable to cut off communication between the auxiliary reservoir and the defective regulating valve or valves. To this end I arrange in the line of such communication a valve-casing A², Fig. 12, having a port a to the pipe A', 105 and ports a' a' a³ to branches A³ A⁴ A⁵, which lead to the several regulating-valves, and adjust within the casing a conical cock A⁶, provided with a handle A⁷, and having a segmental valve-surface A⁸, adapted to close any 110 one of the four ports, leaving the other three open, or to stand between two of the ports when in its normal position, leaving them all open, as shown in the drawings. A cock r is placed in the pipe R for adjusting the capacity of the feed-passage.

Having thus described my several improvements, what I claim as new, and desire to secure by Letters Patent, is as follows:

1. In a railway-air-brake system, in combination with the main reservoir, train-pipe, connecting-passage, and engineer's valve, a limiting-valve actuated by variations of train-

pipe pressure independently of the pressure in the main reservoir, and so arranged that the superior force of the latter pressure tends to hold the valve to its seat when closed, substantially as described.

2. In a railway-air-brake system, the combination of the main reservoir, train-pipe, connecting-passage, and engineer's valve with a valve-seat having a suitable port or ports to which, when open, vent air from the main reservoir to the train-pipe, a valve interposed between said valve-seat and the main-reservoir, and so constructed and arranged with relation to its port or ports that the main-reservoir pressure tends to hold it to its seat when closed, a diaphragm actuated by train-pipe pressure against the resistance of a spring, and a connection from the diaphragm to the valve, whereby the latter is actuated by variations of train-pipe pressure acting upon the diaphragm, substantially as described.

3. In a railway-air-brake system, the combination of a main reservoir and train-pipe with a connecting-passage controlled by the engineer's valve, and with a limiting-valve device consisting of a diaphragm, valve, and spring, said spring being supplemented in its action by fluid-pressure independent of the main-reservoir pressure, combined and operating substantially as described, whereby the spring, aided by its coacting fluid-pressure, tends to hold the valve-port open, and the train-pipe pressure at a predetermined limit above said coacting fluid-pressure closes it.

4. In a railway-air-brake system, the combination of the main reservoir, train-pipe, connecting-passages, engineer's valve, and auxiliary reservoir with a limiting-valve device consisting of a diaphragm, spring, valve, and air-passage from an auxiliary reservoir, which is independent in its pressure from the main air-reservoir to the back of the diaphragm, combined and operating substantially as described, whereby the spring and auxiliary-reservoir pressure coact to hold the valve-port normally open and the train-pipe pressure at a predetermined limit above the auxiliary-reservoir pressure closes it.

5. In a fluid-pressure-brake system, the combination of the engineer's valve with a differential valve governed by the pressure of the auxiliary reservoir of one of the brake mechanisms, substantially as and for the purposes described.

6. In a fluid-pressure-brake system, the combination, with the train-pipe or other air-receptacle the pressure of which is to be regulated, of a separate air-chamber and a diaphragm interposed between them and actuated in opposite directions by the two fluid-pressures, a passage communicating with the train-pipe or air-receptacle the pressure in which is to be regulated, an engineer's valve to open and close said passage at will, a valve controlled by said diaphragm to automatically

govern said passage when it is opened by the engineer's valve, and a spring to aid one of said pressures in holding the valve-port open against the opposition of the other, substantially as described.

7. In a fluid-pressure-brake system, the combination, with the train-pipe or other air-receptacle the pressure in which is to be regulated, of a separate air-chamber the pressure in which corresponds to the pressure in the auxiliary reservoirs of the brake mechanism, and a diaphragm interposed between them and actuated in opposite directions by the two fluid-pressures, a passage communicating with the train-pipe or air-receptacle the pressure in which is to be regulated, an engineer's valve to open and close said passage at will, a valve controlled by said diaphragm to automatically govern said passage when it is opened by the engineer's valve, and a spring to aid one of said pressures in holding the valve-port open against the opposition of the other, substantially as described.

8. In a fluid-pressure-brake system having governing-valves provided or combined with refilling-passages to permit the refilling of the auxiliary reservoirs from the train-pipe while the brakes are set without releasing them, the combination of the main reservoir and train-pipe with a feed-passage leading from the source of the fluid-pressure to the train-pipe, an engineer's valve to open and close the same, and means for independently adjusting the capacity of the feed-passage, substantially as described.

9. In a fluid-pressure-brake system having governing-valves provided or combined with refilling-passages to permit the refilling of the auxiliary reservoirs from the train-pipe while the brakes are set without releasing them, the combination of the following elements, viz: a feed-passage leading from the source of fluid-pressure to the train-pipe, an engineer's valve to open and close said feed-passage at will, and means for limiting the head of feed-pressure to a predetermined amount above the train-pipe pressure, substantially as described.

10. In a fluid-pressure-brake system having governing-valves provided or combined with refilling-passages to permit the refilling of the auxiliary reservoirs from the train-pipe while the brakes are set without releasing them, the combination of the following elements, viz: a feed-passage leading from the source of fluid-pressure to the train-pipe, an engineer's valve to open and close said feed-passage at will, means for independently adjusting the capacity of the feed-passage, and means for limiting the head of feed-pressure to a predetermined amount above the train-pipe pressure, substantially as described.

11. In a fluid-pressure-brake system, the combination of the train-pipe with an expansion chamber arranged between the engineer's valve and the governing-valves, and

located at or near the engineer's valve, substantially as and for the purpose described.

12. In a railway-air-brake system, the combination of a way-cock and its casing adapted 5 to be arranged at or beneath the floor of the cab, with a tubular standard extending upward from the engineer's valve-casing, an operating-shaft extending upward from the way-cock through the tubular standard and provided with a handle at its upper end, a curved plate extending from the standard up over the upper end of the shaft, and a screw supported by said plate and bearing down upon the end of the shaft for the purpose of holding the cock to its seat, substantially as described.

13. In a railway-air-brake system, the combination of a way-cock, a curved indicating plate or rim, a handle so arranged as to leave 20 the upper surface of the plate or rim entirely exposed, and a retaining-spring engaging with the inner or concave edge of the plate or rim to retain the handle in its several positions, substantially as described.

25 14. In a railway-air-brake system, the combination of a way-cock casing, a tubular standard enlarged at its lower end to screw into the top of the casing, a screw or pin to retain the standard in proper relation to the casing, 30 a way-cock arranged in the casing, a shaft extending up from the engineer's valve and provided with a handle, a curved plate extending from the standard up over the top of the shaft and held in proper relation to the standard by a screw or pin, a screw extending through the curved plate and bearing downward upon the upper end of the shaft, and an indicating-plate or retaining-spring, substantially as described.

40 15. In a railway-air-brake system provided with means for applying the auxiliary-reservoir pressure of the tender to regulate the flow of air to or from the train-pipe at the engine, the combination of the brake-applying rods and levers of the tender with a spring to reduce the effective force of the air-pressure upon the brakes, substantially as and for the purposes described.

16. In a railway-air-brake system provided 50 with means for applying the auxiliary-reservoir pressure of the tender to regulate the flow of air to or from the train-pipe at the engine, the combination of a pipe leading from said auxiliary reservoir, a valve-casing connected to said pipe, branch pipes or passages leading from said valve-casing to the regulating devices, and a cock arranged in said casing adapted to open all the pipes and passages communicating with the casing, or to 55 close any one of them and leave the others open, substantially as described.

17. In a railway-air-brake system, the combination of a valve-casing having a tapering internal chamber circular in cross-section, a 60 pipe A', leading from the auxiliary reservoir of the tender to said chamber, branch pipes or passages leading from said chamber to de-

vices for regulating the flow of air to and from the train-pipe, and a cock arranged in said chamber, provided with a handle and 70 adapted to open all the ports of the chamber or to close any one of them and leave the others open, substantially as described.

18. In a railway-air-brake system operated by varying, by movements of the engineer's 75 brake-valve, the relation between the air-pressure in the train-pipe and the air-pressure in the auxiliary reservoirs along the train, and provided with a valve controlled by a piston or diaphragm for automatically limiting the extent of such variation, the herein-described method of governing the action of said valve, consisting, essentially, in subjecting said piston or diaphragm on one side to an air-pressure whose variations substantially 85 coincide with those of the train-pipe and on the other side to an air-pressure whose variations substantially coincide with those of the auxiliary reservoirs along the train.

19. In an engineer's brake-valve, the combination of a piston or diaphragm and a connected discharge-valve controlling the exhaust of air from a brake-pipe, said piston or diaphragm being adapted to close the discharge-valve by a disturbance of equilibrium 95 of pressure to a predetermined extent on its opposite sides and to open and maintain the opening of the discharge-valve by a restoration of such equilibrium, whereby, when the engineer's valve is opened, the flow of air 100 from the brake-pipe is automatically regulated, substantially as described.

20. In an engineer's brake-valve, the combination of a piston or diaphragm and a connected supply-valve controlling the supply of 105 air from the main reservoir to the brake-pipe, said piston or diaphragm being adapted to close the supply-valve by a disturbance of equilibrium of pressure to a predetermined extent on its opposite sides and to open and 110 maintain the opening of the supply-valve by restoration of such equilibrium, whereby, when the engineer's valve is opened to the reservoir-port, the flow of air into the brake-pipe is 115 automatically regulated, substantially as described.

21. In a railway-air-brake system, the combination of a brake-pipe or other air-receptacle whose pressure is to be reduced, an exhaust-passage therefrom controlled at one 120 point by a hand-valve and at another point by an automatic valve, and a piston or diaphragm connected to the automatic valve and adapted to close the same by a disturbance of equilibrium of pressure to a predetermined 125 extent on its opposite sides and to open and maintain the opening of the same by a restoration of such equilibrium, whereby, when the engineer's valve is opened, the flow of air from the brake-pipe is automatically regulated, 130 substantially as described.

22. In a railway-air-brake system, the combination of a brake-pipe or other air-receptacle whose pressure is to be increased, a sup-

ply-passage leading from the main reservoir to said brake-pipe or receptacle, controlled at one point by a hand-valve and at another point by an automatic valve, and a piston or 5 diaphragm connected to the automatic valve and adapted to close the same by a disturbance of equilibrium of pressure to a predetermined extent on its opposite sides and to open and maintain the opening of the same 10 by a restoration of such equilibrium, whereby, when the engineer's valve is opened to the reservoir-port, the flow of air into the brake-pipe is automatically regulated, substantially as described.

15 23. In an engineer's brake-valve, the combination of a piston or diaphragm and a connected discharge-valve controlling the exhaust of air from a brake-pipe, with a spring or its equivalent to oppose the closing of the 20 valve, said piston or diaphragm being adapted to close the discharge-valve by a disturbance of equilibrium of pressure on its opposite sides sufficient to enable it to overcome the resistance of the spring and to permit the spring 25 to open and maintain the opening of the discharge-valve upon the restoration of such equilibrium, substantially as described.

24. In an engineer's brake-valve, the combination of a piston or diaphragm and a connected supply-valve controlling the supply of air from the main reservoir to the brake-pipe, with a spring to oppose the closing of the valve, said piston or diaphragm being adapted to close the supply-valve by a disturbance of equilibrium of pressure on its opposite sides sufficient to enable it to overcome the resistance of the spring and to permit the spring to open and maintain the opening of the supply-valve upon the restoration 40 of such equilibrium, substantially as described.

25. In a railway-air-brake system, the combination of a brake-pipe or other air receptacle whose pressure is to be reduced, an exhaust-passage therefrom controlled at one point by a hand-valve and at another point by an automatic valve, and a piston or diaphragm connected to the automatic valve, with a spring to resist the closing of said 50 valve, said piston or diaphragm being adapted to close the automatic valve by a disturbance of equilibrium of pressure on its opposite sides sufficient to enable it to overcome the resistance of the spring and to permit the spring to 55 open and maintain the opening of said valve upon the restoration of such equilibrium, substantially as described.

26. In a railway-air-brake system, the combination of a brake-pipe or other air-receptacle whose pressure is to be increased, a supply-passage leading from the main reservoir to said brake-pipe or receptacle, controlled at one point by a hand-valve and at another point by an automatic valve, and a piston or 65 diaphragm connected to the automatic valve, with a spring to resist the closing of said valve, said piston or diaphragm being adapted to

close the automatic valve by a disturbance of equilibrium of pressure on its opposite sides sufficient to enable it to overcome the resistance of the spring and to permit the spring to open and maintain the opening of said valve upon the restoration of such equilibrium, substantially as described.

27. In an engineer's brake-valve, the combination of an automatic discharge-valve controlling the exhaust of air from a brake-pipe or other air-receptacle whose pressure is to be reduced, a piston or diaphragm connected to said valve, adapted to close the same by a disturbance of equilibrium of pressure to a predetermined extent on its opposite sides and to open and maintain the opening of the same by a restoration of such equilibrium, and a valve actuated by hand for effecting an exhaust of air through the passage controlled by the automatic valve at one side of the piston or diaphragm, and for causing by the same movement a slower exhaust of the air at the opposite side of the piston or diaphragm, substantially as described, whereby, when the hand-actuated valve is open, the automatic valve is so controlled by the two varying air-pressures as to initially permit the one to reduce to the predetermined extent below the other, and then to allow both to reduce together without any substantial disturbance of the difference thus initially established.

28. In an engineer's brake-valve, the combination of an automatic supply-valve controlling the admission of air from the main reservoir to a brake-pipe or other air-receptacle whose pressure is to be increased, a piston or diaphragm connected to said valve, adapted to close the same by a disturbance of equilibrium of pressure to a predetermined extent on its opposite sides and to open and maintain the opening of the same by a restoration of such equilibrium, and a valve actuated by hand for effecting an increase of pressure through the passage controlled by the automatic valve at one side of the piston or diaphragm, and for causing by the same movement a slower increase of pressure at the opposite side of the piston or diaphragm, substantially as described, whereby, when the hand-actuated valve is open, the automatic valve is so controlled by the two varying air-pressures as to initially permit the one to rise to the predetermined extent above the other, and then to allow both to rise together without any substantial disturbance of the difference thus initially established.

29. In a railway-air-brake system, the combination of a brake-pipe or other air-receptacle whose pressure is to be reduced, an exhaust-passage therefrom controlled at one point by a hand-valve and at another point by an automatic valve, a spring to resist the closing of the automatic valve, a piston or diaphragm connected to the automatic valve, adapted to close the same by a disturbance of equilibrium of pressure on its opposite

sides sufficient to enable it to overcome the resistance of the spring and to permit the spring to open and maintain the opening of the same upon the restoration of such equilibrium, and an air-passage effecting a communication between the auxiliary reservoir of one of the brake mechanisms and that side of the piston or diaphragm which is most remote from said exhaust-passage, substantially as described.

30. In a railway-air-brake system, the combination of a brake-pipe or other air-receptacle whose pressure is to be increased, a supply-pipe leading from the main reservoir to said brake-pipe or receptacle, controlled at one point by a hand-valve and at another point by an automatic valve, a spring to resist the closing of the automatic valve, a piston or diaphragm connected to the automatic valve, adapted to close the same by a disturbance of equilibrium of pressure on its opposite sides sufficient to enable it to overcome the resistance of the spring and to permit the spring to open and maintain the opening of the same upon the restoration of such equilibrium, and an air-passage effecting a communication between the auxiliary reservoir of one of the brake mechanisms and that side of the piston or diaphragm which is most remote from said supply-passage, substantially as described.

31. In a railway-air-brake system operated by varying the relation between the air-pressure in the train-pipe and the air-pressure in the auxiliary reservoirs along the train, a controlling-valve for automatically limiting such variation, said valve being so connected as to be operated by the differences of pressure in the train-pipe and auxiliary reservoirs, substantially as and for the purpose set forth. 35 40

32. In a railway-air-brake system, the combination of a train-pipe, an engineer's valve, a controlling-valve connected to the engineer's valve, and a pipe or passage connecting the controlling-valve with one of the auxiliary 45 reservoirs of the train, substantially as and for the purpose set forth.

33. In a railway-air-brake system, the combination of a train-pipe, an engineer's valve, a controlling-valve regulating the flow of air 50 through a port or passage leading into the train-pipe, and a pipe or passage connecting the controlling-valve with one of the auxiliary reservoirs of the train, substantially as and for the purpose set forth.
